STRINGED MUSICAL INSTRUMENT

Calvert A. Dawson, 4680 Gibbens Payne Drive,
East Baton Rouge Parish, La. 70714

Filed Mar. 18, 1971, Ser. No. 125,909

Term of patent 14 years

Int. Cl. D17—03

U.S. Cl. D56—1

FIG. 1 is a perspective view of a stringed musical instrument, specifically a mandolin-guitar combination, embodying my new design,

FIG. 2 is a top plan view thereof, and

FIG. 3 is a left side elevational view thereof.

I claim:

The ornamental design for a stringed musical instrument, substantially as shown.
